(57) **CLAIM**

We claim the ornamental design for a tire tread, as shown and described.

DESCRIPTION

FIG. 1 is a top perspective view of the tire tread according to the new design.

FIG. 2 is a bottom perspective view of the tire tread shown in FIG. 1.

FIG. 3 is a front elevation view of the tire tread shown in FIG. 1.

FIG. 4 is a rear elevation view of the tire tread shown in FIG. 1.

FIG. 5 is left side elevation view of the tire tread shown in FIG. 1.

FIG. 6 is a right side elevation view of the tire tread shown in FIG. 1.

FIG. 7 is a top plan view of the tire tread shown in FIG. 1; and,

FIG. 8 is a bottom plan view of the tire tread shown in FIG. 1.

The broken lines in the drawings illustrate portions of the tire tread that form no part of the claimed design.
